DESIGN FOR A COMBINED IDENTIFICATION TAG AND MONEY CLIP

Hyman Samuel Kirsch, Woodmere, N. Y.

Application May 11, 1945, Serial No. 119,488

Term of patent 7 years

(Cl. D74—2)

To all whom it may concern:

Be it known that I, Hyman Samuel Kirsch, a citizen of the United States, residing in Woodmere, Long Island, in the county of Nassau and State of New York, have invented a new, original, and ornamental Design for a Combined Identification Tag and Money Clip, of which the following is a specification, reference being had to the accompanying drawing, forming part thereof.

I claim:

The ornamental design for a combined identification tag and money clip, substantially as shown.

HYMAN SAMUEL KIRSCH.
